Primary Examiner — Catherine Ho

(74) *Attorney, Agent, or Firm* — CANTOR COLBURN LLP

(57) **CLAIM**

The ornamental design for a tag for PCR tube, as shown and described.

DESCRIPTION

FIG. 1 is a perspective view of a tag for PCR tube, showing my new design in a first embodiment;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a perspective view of a tag for PCR tube, showing my new design in a second embodiment;

FIG. 9 is a front view thereof;

FIG. 10 is a rear view thereof;

FIG. 11 is a side view thereof;

FIG. 12 is an opposite side view thereof;

FIG. 13 is a top view thereof; and,

FIG. 14 is a bottom view thereof.

The broken lines show portions of the article that form no part of the claimed design.

1 Claim, 14 Drawing Sheets
